(57) **CLAIM**

The ornamental design for a liquid soap container, as shown and described.

DESCRIPTION

FIG. 1 is a top, front, and right side perspective view of the liquid soap container showing my new and ornamental design;

FIG. 2 is a bottom, front, and right side perspective view thereof, shown at a reduced scale;

FIG. 3 is a left side elevational view thereof, the right side elevational view being a mirror image except for the thread;

FIG. 4 is a rear elevational view thereof;

FIG. 5 is a front elevational view thereof; and,

FIG. 6 is a bottom plan view thereof.
